CURT HILSCHER, OF CHEMNITZ, GERMANY

THREAD TENSIONING DEVICE

Application filed January 8, 1930, Serial No. 419,298, and in Germany August 1, 1929.

The present invention relates more particularly to an improvement in thread tensioning devices adapted to be used in connection with fabric forming machines such as knitting machines and the like. One object thereof has been to provide a tension device of relatively simple and inexpensive construction which may readily be attached to and detached from a fabric forming machine without removing or disturbing the fabric forming instrumentalities thereof. A further object of the invention has been to provide in such a tensioning device, a readily adjustable thread guiding member capable of angular adjustment with respect to its base to increase or diminish the frictional effect as the thread moves or is drawn therethrough.

A preferred embodiment of my invention is illustrated in the drawing forming a part 20 of the present specification and in which:

Figure 1 is an end elevation;

Figure 2, a side elevation;

Figure 3, a top plan view;

Figure 4, a fragmentary view in perspective illustrating more particularly the construction of the metallic base or supporting member; and

Figure 5, a bottom plan view of a rotatable thread guide member.

Referring to the drawing, the embodiment of my invention therein shown, includes a base formed from a single strip of material preferably metal and bent to provide resilient clamping legs or portions 1 and 2 extending from an intermediate rigid thread guide supporting portion 3. Lugs 4 are struck up out of the material of the clamping legs 1 and 2 and are provided with openings within which are secured non-metallic

bushings 5, preferably of porcelain, glass or other suitable material each having an opening through which a thread 11 or the like may be drawn with a minimum of frictional effect. The resilient leg 1 has its lower end bent to 45 form a transversely extending portion 6

adapted to limit the extent of downward movement of the tensioning device when it is applied to a guide carrying rod or bar or the like of a fabric forming machine, as the guide carrying bar 7 of a knitting machine. 50

As indicated more clearly in Figure 4, the intermediate portion 3 of the base is provided with an opening 8 adapted to receive a portion of a non-metallic thread guide member 9 having an opening 10 to receive the thread 11 or the like. The guide member 9 is preferably made of a non-metallic material such as porcelain, glass or other suitable material to present a minimum of frictional resistance to passage of the thread 11 and is formed with an upwardly exposed transverse ridge 12 forming a thumb piece whereby the guide member may be rotated to different positions of adjustment with respect to the base. A lower portion 17 of said guide member is of reduced cross sectional area and passes through and engages the opening 8. The shoulder formed between the main portion of the guide member and reduced lower portion 17 is provided on its under side with suitable deformations as the corrugations 13, Figure 5. The extreme lower end of the guide member is of further reduced cross sectional area and is provided with a hole 14 adapted to receive a cotter pin 15 or the like, said lower end forming with the portion 17 a shoulder 16. A washer 18 is interposed between said pin 15 and the shoulder 16. A spring 19 is interposed between a lower surface of the intermediate portion 3 of the base and an upper surface of said washer 18 and is adapted to retain the guide member in yielding frictional engagement with said intermediate portion 3. 75

As shown more clearly in Figure 4, a plurality of deformations 20 are formed in a portion of the upper surface of the intermediate portion 3 of the base and adjacent to the opening 8, said deformations being positioned and adapted to cooperate with the 80 85 90

corrugations 13 on the guide member 9 and to act as detents to prevent undesired angular movement of said guide member 9 relatively to the base.

- 5 In operation, with the tensioning device secured as indicated in Figure 1, a thread such as 11 is drawn through the guide bushings 5 and the hole 10 of guide member 9. For minimum tension on said thread, guide member 9 is turned to bring its opening 10 into alignment with the openings of the guide bushings 5. To increase tension on the thread 11, the guide member 9 is turned by means of the thumb piece 12 to any desired 15 angular position in relation to the base where it is held in frictional engagement with said base by means of the spring 19 as above described.

I claim as my invention:

- 20 1. A thread tension device comprising a base, a thread guiding member rotatably mounted on said base, means for releasably retaining said member in yielding engagement with said base, and detent means for retaining said member in any desired position of angular adjustment with respect to said base.
- 25 2. A thread tension device comprising a base formed of a single piece of metal bent to provide resilient clamping portions and a guide supporting portion provided with a guide receiving opening and deformations adjacent thereto, a thread guide member having a portion extending through said opening and another portion provided with deformations positioned to cooperate with said deformations on the guide supporting portion of said base, and a spring operatively interposed between said guide member and said 30 base to retain said member and said base in yielding frictional engagement.
- 35 3. A thread tension device comprising a base formed of a single piece of metal bent to provide cooperating resilient clamping portions and an intermediate portion provided with a guide receiving opening, a non-metallic thread guide member having one end extending through said intermediate portion, and a spring cooperating with said end and bearing against said guide supporting portion to retain said non-metallic guide member in yielding frictional engagement with said guide supporting portion.
- 40 4. A thread tension device comprising a base, thread guides mounted thereon in spaced relation, a rotatably adjustable thread guiding member mounted on said base in operative relation to said thread guides, and means for releasably retaining said member in yielding engagement with said base at any desired position of angular adjustment with respect thereto.
- 45 5. A thread tension device comprising a base provided with an opening to receive a thread guiding member, a thread guiding

member having one end extending through said opening and rotatably adjustable in relation to said base, and a spring cooperating with said member and bearing against one side of said base to releasably retain said guiding member in yielding engagement with a portion of the opposite side of the base and in any desired position of angular adjustment with respect thereto.

In testimony whereof, I have signed my name to this specification this 19th day of December, 1929.

CURT HILSCHER.
